UNITED STATES PATENT OFFICE

163,934

NECKLACE OR SIMILAR ARTICLE

Michael Chernow, New York, N. Y.

Application April 15, 1950, Serial No. 9,250

Term of patent 7 years

(Cl. D45—16)

To all whom it may concern:

Be it known that I, Michael Chernow, a citizen of the United States and residing at New York, in the county of New York and State of New York, have invented a new, original, and ornamental Design for a Necklace or Similar Article, of which the following is a specification, reference being had to the accompanying drawing, forming part thereof, and in which

Fig. 1 is a perspective view of the necklace or similar article, showing my new design,

Fig. 2 is an enlarged fragmentary front elevational view showing the slide and pendant portions of the necklace, sections of the chains being broken away for convenience of illustration only, and

Fig. 3 is a side elevational view of the fragmentary portion shown in Fig. 2.

I claim:

The ornamental design for a necklace or similar article, substantially as shown.

MICHAEL CHERNOW.
